(57) CLAIM

The ornamental design for a wall lamp as shown and described.

DESCRIPTION

FIG. 1 is a front elevational view of a wall lamp showing my new design;

FIG. 2 is a right side view thereof;

FIG. 3 is a top plan view thereof; and,

FIG. 4 is a perspective view thereof.

The left side view is a mirror image of the right side view. The broken lines in the drawings illustrate portions of the wall lamp and form no part of the claimed design.
